UNITED STATES PATENT OFFICE.

CHARLES F. SCHWANENGEL, OF DAYTON, OHIO, ASSIGNOR OF ONE-HALF TO WILLIAM M. BUTZ, OF DAYTON, OHIO.

HYDRAULIC VISE.

978,067.

Specification of Letters Patent.

Patented Dec. 6, 1910.

Application filed June 16, 1910. Serial No. 567,307.

To all whom it may concern:

Be it known that I, CHARLES F. SCHWANENGEL, a citizen of the United States, residing at Dayton, in the county of Montgomery and State of Ohio, have invented certain new and useful Improvements in Hydraulic Vises; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in hydraulic vises.

The object of the invention is to provide a vise of the above type that is simple and durable in construction, efficient in operation, and which may be used as a jack should occasion require.

Referring to the accompanying drawings, Figure 1 is a top plan view of my improved hydraulic vise partially in section. Fig. 2 is a side elevation of the same partially in section. Fig. 3 is a sectional view of the same on the line *a—a* of Fig. 1. Fig. 4 is a sectional view on the line *b—b* of Fig. 2. Fig. 5 is a front elevation partially in section.

Throughout the specification and drawings, similar reference characters indicate corresponding parts.

Referring more particularly to the drawings, 1 designates a base provided at its rear end with a chamber 2. Mounted in the chamber, and supported by the walls thereof, is a cylinder 3 in which a ram 4 is adapted to reciprocate. The end of the ram within the cylinder is provided with a suitable cup packing 5, while the other end is provided with a vise jaw 6. The vise jaw 6 works in connection with a vise jaw 7 provided with a boss 8 which lies in a bearing 9, thereby allowing the jaw 7 to rock or oscillate. The jaw 6 may be similarly rocked, the plunger 4 acting as a pivot. The jaw 7 is held in the bearing 9 by a suitable key 9^a. To prevent the jaws rocking when once placed in a desired position, there is provided in the boss 8 a suitable number of recesses 10 adapted to receive a pin 11 controlled by a spring 12, see Fig. 5. The pin 11 and spring 12 lie in a recessed boss 13, and the outer

end of the pin 11 is provided with a finger piece 14 by means of which said pin may be withdrawn from one of the recesses 10 to allow the jaws 6 and 7 to be rocked to a different position. It will be seen that the axis of the jaw 7 is in line with the axis of the ram upon which the jaw 6 is rigidly mounted. Owing to this, the work may be turned to one side without removing it from the vise.

It will be seen that, if hydraulic pressure can be brought to bear on the end of the ram 4 within the cylinder 3, the jaws 6 and 7 will be pressed together and any article placed between said jaws will be held rigidly. This pressure is brought to bear as follows. Mounted on the side of the chamber by means of screws 14^a or other suitable means, is a pump housing 15 within which is a pump cylinder 16 inclosing a reciprocating piston 17 provided with suitable packing 18. The piston 17 is attached to an extension 19 which projects out of the housing 15 where it is attached to a pivotal member 21 by means of a screw 22. The member 21 is pivoted at 23 and is provided with a socket 24 adapted to receive a hand lever 25. The member 21 is also provided with a projection 26 that engages the extreme end of the piston extension 19 when the piston is moved inwardly, thereby taking the pressure off the screw 22. It will thus be seen that the piston 17 is reciprocated by means of the hand lever 25, and when it is thus reciprocated it will draw the liquid from the chamber 2, which acts as a reservoir, during its outward movement, and forces said liquid into the cylinder 3 back of the ram during its inward movement. The liquid is drawn into the pump cylinder 16 through a curved tube 27 provided with a screen 29, see Fig. 3. The passage-way formed by the tube 27 is controlled by a valve 30 which prevents the liquid flowing back into the reservoir or chamber 2. The liquid is forced out of the cylinder 16 through a tube 31 which opens into the ram cylinder 3. The passage-way through the tube 31 is controlled by a valve 32 which prevents the liquid in the ram cylinder, flowing back into the pump cylinder. Both valves 30 and 32 are provided with leather faces which take up any unevenness of the valve seats due to wear or foreign substances entering them.

The ram cylinder 3 is provided with a release valve 33 mounted in a housing 34 supported in a boss 35. The said valve 33 is spring-controlled and provided with a 5 stem 36 adapted to be engaged by a rod 37 extending out of the chamber wall 2 where it is engaged by a lever 38.

When it is desired to use the vise the lever 38 is thrown inwardly, which opens 10 the valve 33 and releases the liquid, under pressure, back of the ram 4. The vise jaw 6 may then be pushed back a distance sufficient to receive the article desired to be held in the vise. The release valve is then 15 closed and the pump piston is reciprocated by means of the lever 25. During this reciprocating movement the liquid is drawn in from the reservoir or chamber 2, and is forced into the cylinder 3 under pressure. 20 As the ratio between the diameter of the ram 4 and the piston 11 is quite large, the liquid within the cylinder 3 may be placed under great pressure, which pressure holds the article between the vise jaws. When 25 it is desired to remove the article in the vise, the release valve 33 is opened, as before described.

The cylinder 3 is provided with a wiping ring 39 of felt or any suitable material, 30 which prevents foreign matter entering between the ram and the cylinder. The cap 2^a of the chamber 2 is provided with an air vent 40, filled with felt which prevents the entrance of foreign matter, see Fig. 2. -

35 The base 1 is provided with lugs 41 by means of which it may be attached to a bench.

The device may be used as a jack as follows. Projecting through the jaw 7 and 40 the bearing is a standard or rod 42 rigidly attached to the jaw 6 by any suitable means. The rod 42 is splined to the jaw 7 by a key 44, which compels the two jaws 6 and 7 to rock concurrently. The outer end of said 45 rod 42 is provided with a recessed head 43 adapted to engage the article to be lifted. When used as a jack, the release valve 33 is opened to allow the head 43 to recede. The device is then placed vertically under 50 the article to be lifted and the lever 25 is reciprocated the same as when used as a vise.

I claim:

1. In a device of the type specified, a base, 55 a reservoir mounted on said base, a cylinder mounted in said reservoir, a ram adapted to reciprocate and oscillate in said cylinder, a vise jaw mounted on said ram, a second vise jaw pivotally mounted on said base the axis 60 of said jaw being in line with the axis of

the ram, and a pump adapted to force liquid from the reservoir into the cylinder behind the ram.

2. In a device of the type specified, a base, 65 a reservoir mounted on said base, a cylinder mounted in said reservoir, a ram adapted to reciprocate and oscillate in said cylinder, a vise jaw mounted on said ram, a second vise jaw pivotally mounted on said base, means whereby both of said jaws are compelled to rock or oscillate concurrently, and a pump adapted to force a liquid from the reservoir into the cylinder back of the ram.

3. In a device of the type specified, a base, 75 a reservoir mounted on said base, a cylinder mounted in said reservoir, a ram adapted to reciprocate and oscillate in said cylinder, a vise jaw mounted on said ram, a second vise jaw pivoted on said base, means for locking said second jaw in a set position, and a pump 80 adapted to force liquid from the reservoir into the cylinder back of the ram.

4. In a device of the type specified, a base, 85 a reservoir mounted on said base, a cylinder mounted in said reservoir, a ram adapted to reciprocate and oscillate in said cylinder, a vise jaw mounted on said ram, a second vise jaw pivotally mounted in said base, means whereby both of said jaws may rock or oscillate concurrently, means for locking both of 90 said jaws in a set position, and a pump adapted to force liquid from the reservoir into the cylinder back of the piston.

5. In a device of the type specified, a base, 95 a reservoir mounted on said base, a cylinder mounted in said reservoir, a ram adapted to reciprocate in said cylinder, a vise jaw mounted on said ram, a second vise jaw mounted on said base, a rod mounted on said ram, and extending through said second jaw, whereby said device may be used as a jack, and a pump adapted to force liquid 100 from the reservoir into the cylinder back of the ram.

6. In a hydraulic vise, the combination 105 with a base, a vise jaw mounted on said base, a reservoir mounted on said base, a cylinder mounted in said reservoir, of a ram adapted to reciprocate in said cylinder, said ram having as a part thereof a vise jaw co-operating with the vise jaw on the base, and an elevating standard extending from the vise jaw on the ram through the vise jaw on the base, substantially as specified.

In testimony whereof I affix my signature, 115 in presence of two witnesses.

CHARLES F. SCHWANENGEL.
